United States Patent Office

Des. 212,061

Patented Aug. 20, 1968

212,061

SEWING MACHINE

Henry Dreyfuss, South Pasadena, Calif., assignor to The Singer Company, New York, N.Y., a corporation of New Jersey

Filed Sept. 27, 1967, Ser. No. 8,750

Term of patent 14 years

(Cl. D70—1)

FIG. 1 is a front elevational view of a sewing machine showing my new design.

FIG. 2 is a rear elevational view thereof.

FIG. 3 is a top plan view.

FIG. 4 is an end view as seen from the left of FIG. 1.

FIG. 5 is an end view as seen from the right of FIG. 1, and

FIG. 6 is a front perspective view.

I claim:

The ornamental design for a sewing machine, substantially as shown.
